DESIGN.

M. HIRST & H. P. ROBINSON.

RUG.

No. 16,966.

Patented Nov. 2, 1886.

UNITED STATES PATENT OFFICE.

MATTHEW HIRST AND HARRY P. ROBINSON, OF PHILADELPHIA, PA.

DESIGN FOR A RUG.

SPECIFICATION forming part of Design No. 16,966, dated November 2, 1886.

Application filed September 20, 1886. Serial No. 214,102. Term of patent 3½ years.

To all whom it may concern:

Be it known that we, MATTILEW HIRST and HARRY P. ROBINSON, both of Philadelphia, Pennsylvania, have invented a new Design for Rugs, of which the following is a full and exact description, reference being had to the accompanying photographic illustration, making part hereof.

In the said illustration, A is a central panel, 10 contrasting in shade distinct from the background, a bird with spread wings B, holding in suspension a flag, C, dependent from which latter is a star, D. The panel A is round in shape. The central panel is flanked on one 15 side by a panel, E, containing the representation of a tent, F, with a camp-fire, G, before it, and on the other side by a panel, H, containing the representation of a ship, I, with spars J. These three panels are inclosed by a 20 rectangular border of stars, K K. The flag is what is known as the "American flag," and is ornamented with stripes and a "union" of stars.

L is a line of stars inside of panel A.

The essential features of our design for rugs 25 will be fully set forth by the following claim.

What we claim as new is—

The design for rugs, consisting of a panel, A, ornamented with the figure of a bird holding in suspension a flag, dependent from which latter is a star, said panel A being flanked by panels E and H, one of said last-named panels being ornamented by the representation of a tent and the other by that of a ship, substantially as described and shown.
